UNITED STATES PATENT OFFICE.

WILLIAM J. KEENE, OF CHICAGO, ILLINOIS, ASSIGNOR TO CHICAGO SPRING BUTT COMPANY, OF CHICAGO, ILLINOIS, A CORPORATION.

SPRING HINGE.

Application filed October 10, 1921. Serial No. 506,738.

My invention relates to double-acting spring hinges of the type wherein the same spring serves to oppose movement of the hinge in either direction from a predetermined position.

The principal objects of my invention are to provide an improved double-acting spring hinge of the character above referred to; to house mechanism so that the operating parts are enclosed and held against displacement; to provide an external connection of the spring mechanism with the companion hinge member; to afford a more substantial bearing at the pivotal connection of the two main hinge elements; to permit adjustment for optionally selecting the position at which the gate or door is to be normally held by the hinge; to improve the construction so that a more simple and durable form of spring may be employed and wear and tear on the parts materially lessened; to provide a detachable mounting for the completed hinge; and in general, to improve the construction so that the hinge is more desirable than devices of this character which have been available heretofore.

On the drawings:

Fig. 1 is a vertical sectional view of a hinge structure embodying my invention;

Fig. 2 is a horizontal sectional view on the line 2—2 of Fig. 1;

Fig. 3, a side view of the internal mechanism of the hinge with the rib of the casing shown in section on the line 3—3 of Fig. 1;

Fig. 4, a fragmentary view of a gate mounted in position with my improved hinge and showing the companion hinge, which I employ in connection with my double acting spring hinge;

Fig. 5, a view partly in horizontal section showing the manner of temporarily mounting a screen or small door in a doorway, and

Fig. 6, a face view of the detachable bracket structure, shown in Fig. 5.

On the drawings, the reference numeral 1 indicates a post to which a gate 2 is pivoted by means of my improved hinge structures, which are indicated as a whole at 3 and 4 respectively, the latter comprising a double acting spring hinge which maintains the

gate 2 in a predetermined position and permits it to swing either way.

The hinge structure 4 comprises an inverted cup-shaped casing 5 having a flat top, which fits against the lower edge of the gate 2 and is secured to the latter by the screw 6 and there is also an extension 7 extending laterally from the casing 5 at the top under the lower edge of the gate 2 and secured to the latter by the screws 8. The casing 5 is preferably circular in horizontal section and has a circular flange 9 depending from the top wall and forming a seat 10 for the upper end of the stem 11, which extends centrally down through the casing 5 and projects from the lower end thereof. The base of the seat 10 is preferably formed with an annular ball race 12 for ball bearings 13 against which the upper end of the stem 11 engages for supporting the weight of the gate and permitting the latter to turn with ease. At one side of the casing 5 is an internal vertically extending rib 14 and at the opposite side an enlargement 15, each of which has a threaded aperture at the lower end to receive the screws 16 whereby a bottom plate 17 is secured over the lower open end of the casing 5 for enclosing and holding assembled, the mechanism of the spring hinge. The plate 17 has a central opening 18 preferably reinforced by a depending flange extending around the opening to afford a suitable bearing for the lower end of the stem 11 and the projecting portion of this stem is squared, as indicated at 19 to fit in a square opening 20 of the bracket 21, which is formed with a side flange 22 or otherwise constructed so as to be secured to the post 1 or any other support to which the gate is desired to be attached.

The stem 11, by reason of the engagement of the square lower end with the square aperture in the bracket 21 is held against turning movement and has within the casing 5 a pair of abutment lugs 23 and 24 at opposite sides and at different elevations, as shown in Figs. 1 and 3. At the upper and lower ends respectively of the stem 11, within the casing 5, are collars 25 and 26 which loosely engage the stem and each is provided with a segmental flange 27 and 28

respectively, and the former terminating in a shoulder 29 adapted to engage against the abutment 23, and the latter terminating in a shoulder 30 adapted to engage against the abutment 24. A coiled spring 31 extends between the collars 25 and 26 and telescopes on the lower and upper extremities respectively of these collars against their annular flanges 34 and 35 respectively and the ends 10 of this spring are bent inwardly, as shown at 32 and engaged in vertical grooves 33 of the segmental flanges 27 and 28 respectively so that the tension of the spring serves to hold the shoulders 29 and 30 against their 15 stops or abutments 23 and 24. For connecting the spring to the casing 5, so that the operation of the gate is under the control of the spring, there is a lateral projection 36 on the flange 34 of the upper collar 25, which engages against one side of the rib 14 of the casing 5, and there is an oppositely facing projection 37 on the lower collar 26, which engages the opposite side of the rib 14, as shown particularly in Fig. 3, the circumferential spacing of these projections being such that in the normal position of the gate, the projections fit up close to the sides of the rib 14.

With this construction, assuming that the gate is swung in the direction of the arrow 38 in Fig. 2, the rib 14 will rotate in a clockwise direction, moving the projection 37 and the collar 26 with it and the shoulder 30 will be withdrawn from the stationary stop 24 on the stem 11. Inasmuch as the lower end of the spring 31 is connected to the collar 26 and the upper end of the spring is connected to the collar 25, which has the shoulder 29 engaged against the stop 23 of the stem 11, the collar 25 and upper end of the spring will be held by the stop 23 against turning movement, with the result that the swinging of the gate in the direction of the arrow 38 puts the spring 31 under sufficient tension, so that when the gate is released it is returned by the spring to the normal position. When on the other hand, the gate is swung in the direction indicated by the arrow 39 in Fig. 2, a reverse action 50 of the spring mechanism takes place—that is, the engagement of the casing rib 14 against the projection 36 causes the collar 25 to rotate around the stem 11 thus withdrawing the shoulder 29 away from the stationary stop 23 and carrying the upper end of the spring 31 with it and at this time the collar 26 and the lower end of the spring is held against turning movement by the engagement of the shoulder 30 against the stationary stop 24 thereby creating a tension of the spring, which serves to return the gate to the normal position when released. From the foregoing it will be observed that there is what may be termed a neutral position 55 to which the gate is automatically returned

by tension of the spring 31, regardless of which direction the gate may be swung, this position being determined by the location of the circumferential gap existing between the projections 36 and 37 when the shoulders 29 and 30 thereof are engaged against the stops 23 and 24 respectively.

It will be observed that with my device, the spring is constructed in a simple form and subjected only to circumferential strains, thereby avoiding breakage, which frequently occurs in other types of double acting hinges of this character and moreover, the actuating mechanism is confined and held in assembled condition in a closed housing with the stem 11 securely held in upper and lower bearings and there is merely a squared end of the stem projecting from the housing, which serves to detachably mount the hinge on the bracket 21.

The companion hinge structure 3, which I employ in connection with the spring structure 4, for pivotally mounting the gate 2, may be of any desired type, a simple and convenient form being shown in Fig. 4. This structure comprises a plate 40, which is mortised into the upper edge of the gate 2 and has a socket 41 forming a bearing for a pin or stud 42 on the underside of the bracket arm 43. This bracket arm may be secured to the post in any convenient manner, as for example by the flange 44 which depends from the end of the arm 43 and is fastened against the side of the post 1.

It is frequently desirable as for example 100 in hospitals to provide some of the doorways with a screen or small door so that the opening is only partially closed, and it is desirable that they may be detachably mounted in any of the doorways and readily removed 105 when they are no longer required. These doors are preferably spring controlled, so as to automatically close and to meet this demand I have provided means whereby a door of this character and controlled by my 110 spring hinge, may be detachably mounted in a doorway. This means comprises upper and lower plates 45, which are secured to the side of the door casing and provided with dovetailed seats 46. A bracket 47 is 115 provided for each plate 45 and has a depending portion 48 suitably tapered and beveled to engage in the dovetailed seat 46, as shown, and each bracket 47 has a laterally projecting arm 49. One of these arms is formed 120 with a square perforation 50 to receive the square extremity of the hinge member 51 on the door 52, said hinge member being constructed in accordance with my invention 125 as shown in Figs. 1, 2 and 3, and described hereinbefore, and the other arm 49 may be provided with any suitable pivotal connection with the door 52 in axial alignment with the stem 50 of the hinge member 51.

While I have shown and described my in- 130

vention in a preferred form, I am aware that various changes and modifications may be made without departing from the principles of my invention, the scope of which is to be 5 determined by the appended claims.

I claim as my invention:

1. In a spring hinge, a bracket adapted to be secured to a support, a casing adapted to be secured to a swinging element and having a ball bearing at the top, a stem pivoted in the bearing in the casing and having its lower end seated in the bracket on the support and held against turning movement, diametrically opposite and oppositely facing 10 abutments on the stem, the casing having an internal rib, collars loosely engaged on the upper and lower portions of the stem and each provided with a flange having a groove therein and terminating in oppositely facing 15 shoulders adapted to engage the abutments, the collars each having a lateral projection facing in opposite directions to engage opposite sides of the rib, and a coil spring extending between the collars and having its 20 ends bent inwardly to engage the grooves and hold the shoulders against said abutments, as and for the purposes described.
2. In a spring hinge, the combination with an upright support, a bracket on the support and having a squared socket, a swing- 25

ing door, a casing secured at the lower corner of the door and having a bearing at the top, a stem pivoted in the bearing and having its lower end squared and projecting from the casing to set in the socket, diametrically opposite and oppositely facing abutment lugs on the stem at different elevations, the casing having an internal vertically extending longitudinal rib at one side and an enlargement at the opposite side, a plate detachably secured at the rib and enlargement over the bottom of the casing and having a bearing opening for the stem, collars loosely engaged on the upper and lower portions of the stem and each provided with a segmental flange terminating in oppositely facing shoulders substantially one above the other and adapted to engage said abutment lugs, flanges on the collars each having a lateral projection facing in directions opposite to 50 that of adjacent shoulders toward each other to engage opposite sides of the rib, the segmental flanges each having a vertical peripheral groove therein adjacent the shoulders and projections, and a coil spring extending between and engaged with the collars and having its ends bent inwardly and engaged in the grooves to normally hold the shoulders against the abutments.

WILLIAM J. KEENE.
